UNITED STATES PATENT OFFICE.

JAMES H. FARRAR, OF PASSAIC JUNCTION, NEW JERSEY.

SWIVEL-LOOM.

No. 815,152.

Specification of Letters Patent.

Patented March 13, 1906.

Application filed July 2, 1902. Serial No. 114,043.

To all whom it may concern:

Be it known that I, JAMES H. FARRAR, a citizen of the United States, residing in Passaic Junction, in the county of Bergen and State of New Jersey, have invented certain new and useful Improvements in Swivel-Looms; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to looms, and it has reference particularly to swivel-looms. It being necessary in this class of looms to stop the action of the picker-stick (which drives the fly or main shuttle) when the swivel-shuttles come into play, disconnection connecting mechanism between the picker-stick and the tappet or cam shaft from which its actuation is primarily derived is commonly resorted to.

The object of this invention is therefore to provide an improved mechanism for thus disconnectionally connecting the picker-stick and tappet or cam shaft in an effective and simple manner.

In view of the foregoing the invention consists in an improved disconnection connecting mechanism between the picker-stick and tappet or cam shaft which comprises a part which is movable for the purpose of being interposed between or removed from between the tappets or other projections on the cam-shaft and a part which transmits the tappets' influence to the picker-stick.

The invention still further consists in certain combinations and arrangements of parts hereinafter described, and finally embodied in the clauses of the claim.

My invention will be found fully illustrated in the accompanying drawings, wherein—

Figure 1 is a view in front elevation of enough of a loom constructed after the principles of my invention to properly illustrate said invention. Fig. 2 is a plan view of that portion of the loom which involves the mechanism for effecting the raising and lowering of the swivel-shuttles and the mechanism for disconnectionally connecting the picker-stick and the cam or tappet shaft. Fig. 3 is a somewhat-enlarged view, in front elevation, of the mechanism for disconnectionally con-

nected the picker-stick and tappet or cam shaft; and Fig. 4 illustrates a detail.

In the loom-frame *a* is journaled the cam or tappet shaft *b*.

c is one of the picker-sticks, fulcrumed at *d* and normally held outwardly by a spring *e*.

In the bearings *f* in one of the side frames of the loom is journaled a shaft *g*, which carries an upwardly-projecting crank *h*, to which the strap *i* of the picker-stick is connected. On this shaft, which is preferably squared, is mounted an arm *j*, in which is fulcrumed, as at *k*, a block or shoe *l*, having a projection *m*, which extends down through a curved slot *n* in the arm *k* and is engaged by the forked end *o* of a bell-crank lever *p*. When the shoe or block is in the position illustrated in Fig. 2, the cams or tappets *q* on the shaft *b* will as they rotate impinge against the block, and so rock the shaft *g*, which will in turn impart actuation to the picker-stick through the arm *h* and strap *i*. The bell-crank lever *p* is held in the position mentioned by a spring *r*. Upon moving the bell-crank lever against the tension of the spring *r* the block will be thrown out of the way of the cams or tappets *q*, so that the actuation of the picker-stick is caused to stop.

s is the frame in which the swivel-shuttles *t* (shown in dotted lines in Fig. 1) move and which is suitably guided for vertical movement in the batten structure *u*. To straps *v* on said frame *s* are connected flexible connections *w*, which extend up and over pulleys *x*, mounted in said batten structure, then toward each other over other pulleys *y*, and then downwardly, where they merge into a common flexible connection *z*. In a bracket 1 is journaled a pair of pulleys 2 3 and a vertical pulley 4.

5 is a lever which is fast with the pulley 3.

The flexible connection *z* passes around the pulley 4 and then around the pulley 3, being connected at its free end to the lever 5 at 7. Then if the lever 5 is moved against the tension of the spring 6 the flexible connections will be released, so that under the action of gravity the frame *s* may drop.

The lever 5 and the shoe or block *l* are adapted to be actuated in common from a jack 8 of a dobby or other form of head motion through the medium of a flexible connection 9, which extends downwardly and is divided near the base of the loom, one section thereof, 10, extending to and being con-

nected with the pulley 3 at 12, and the other section, 11, being connected with the bell-crank lever *p*.

Having thus fully described my invention, 5 what I claim as new, and desire to secure by Letters Patent, is—

1. In a loom, the combination, with the frame, of the cam - shaft, a picker-stick, a rock-shaft, an arm projecting from said rock-shaft, operative connecting means between the rock-shaft and the picker-stick, and a block or shoe carried by said arm and movable into and out of the path of movement of the cam or cams on said cam-shaft, substantially as described. 10

2. In a loom, the combination, with the frame, of the cam-shaft, a picker-stick, a rock- 15

shaft, an arm projecting from said rock-shaft, operative connecting means between the rock-shaft and the picker-stick, a block or shoe 20 carried by said arm and movable in the same into and out of the path of movement of the cam or cams on said cam-shaft, and means for normally holding said block or shoe in the path of said cam or cams on said cam-shaft, 25 substantially as described.

In testimony that I claim the foregoing I have hereunto set my hand this 30th day of June, 1902.

JAMES H. FARRAR.
